(57) **CLAIM**

The ornamental design for a tip holder, as shown and described.

DESCRIPTION

FIG. 1 is a perspective view of the tip holder showing my new design;

FIG. 2 is a front elevation view thereof;

FIG. 3 is a rear elevation thereof;

FIG. 4 is a left side elevation thereof;

FIG. 5 is a right side elevation thereof;

FIG. 6 is a top view thereof;

FIG. 7 is a bottom view thereof;

FIG. 8 is a perspective thereof shown with a tip being held therein and shown in broken lines and forming no part of the claimed invention;

FIG. 9 is a perspective thereof shown with two tips being held therein and shown in broken lines and forming no part of the claimed invention; and,

FIG. 10 shows the loaded tip holder of FIG. 9 attached to a spray gun shown in broken lines and forming no part of the claimed invention.
